RADIO DEVICE FOR SECRET
COMMUNICATION

Anna Ptáček, New York, N. Y.

Application August 9, 1944, Serial No. 548,727

5 Claims. (Cl. 250—6)

1

This invention relates to new and useful improvements in a radio device for secret communications.

More specifically, the invention proposes the construction of a radio device for secret communications characterized by a radio sender and a radio receiver which are synchronized to send and receive on a constantly changing wave length permitting secret communications to be sent between the sender and the receiver and preventing them from being picked up by radio receivers which are not operating at the synchronized wave lengths.

A further object of the invention proposes providing the radio sender and the radio receiver with a knob or the like which may be turned back and forth for adjusting the variable condensers of these sets, and which are operated by electrically controlled synchronous motors which will cause the two devices to have their wave lengths changed in unison permitting the message sent out by the sender to be picked up by the receiver.

Still further the invention proposes the provision of a synchronous motor controlled by a reversing switch for causing the motor to rotate in one direction or the other to rotate the control knob back and forth, together with the provision of electrically controlled means for reversing the switch for the reasons above outlined.

It is a further object of this invention to construct a radio device for secret communication which is simple and durable and which can be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a schematic illustration of a radio device for secret communications constructed in accordance with this invention.

Fig. 2 is an enlarged detail showing a portion of the mechanism indicated in Fig. 1, and particularly showing the intermittent drive to the tuning condenser of the radio sender, this view taken on the line 2—2 of Fig. 3.

Fig. 3 is a schematic structural and wiring diagram of the radio sender.

A radio device, for secret communications, according to this invention includes a radio sender 10 having an antenna 11 and having as here shown a knob 12 which may be turned back and

2

forth for causing the radio sender to send messages out through the antenna 11 on varying wave lengths. The device further includes a radio receiver 13 having an antenna 14 and having as here shown a knob 15 which may be turned back and forth to cause the radio receiver to be adjusted to the wave length of the radio sender to pick up messages being sent out thereby.

10 Each of the knobs 12 and 15 is in the form of a gear attached to a shaft 16, connected for tuning a variable condenser, these condensers of like design, and of like capacitance on having their movable plates given like degrees of rotation. The condenser of the radio sender is indicated at 17 in Fig. 2. Automatic means, housed as indicated at 19 in Fig. 2, is provided for turning each of the gears 12 and 15 back and forth in short periods synchronized with each other. Said means, and the synchronizing means, are shown in detail in Fig. 3, taken with Fig. 2.

The automatic means 19 is alike for the radio sender 10 and for the radio receiver 13, and is characterized by a synchronous motor 20 with a transmission extended between the synchronous motor and the knob 12 or 15. The automatic means 19 will be described in connection with the radio sender 10 and its knob 12 and the same description applies to the automatic means for the radio receiver 13 and its knob 15.

The synchronous motor 20 has a projected driven shaft 21 and an adjacent shaft 22 which carries a gear 23. A sprocket chain 24 extends over the gear 23 and the gear 12 for turning the shaft 16 when the shaft 22 is rotated. A Geneva drive 25 is interposed between the driven shaft 21 and the shaft 22 for causing the shaft 22 to be intermittently driven from continuously driven shaft 21.

The type of Geneva movement shown is one long well-known as a satisfactory such movement which is reversible as to the direction of drive from the driving element to the driven element.

45 The driving element, fixed on the shaft 21, is a disc 40 having a projection carrying an upstanding driving pin 41, for fractionally rotating a driven element 42 fixed on the shaft 22 to be intermittently fractionally rotated. As is familiar in the art of devices of this kind, following each complete revolution of element 40 said pin enters one of a plurality of radial slots in the driven element 42 spaced uniformly around the same, and thereby there is imparted to the 55 driven element a rotation through 60°, since six

of these slots are here shown. Between adjoining slots of the driven element 42, the periphery of the latter is arcuately concave to match the circularly rounded portion of the periphery of the driving element 40, so that for a part of each revolution of element 40, while the pin 41 is idle relative to a slot of the driven element 42, the latter is locked to the element 40 to prevent movement of the driven element 42. Beyond each opposite end of said circularly rounded portion of the periphery of the driving element 40, said element is arcuately concavely cut away so as not to interfere with arcuate sweep of the points of maximum diameter around the element 42, which points mark the outer ends of its radial slots. In a reversing Geneva movement of the kind described, it is customary, when the slightest accidentally angular shift of the driven element is to be prevented, to rely on a friction clutch, such as indicated at 43, to prevent any possibility of such shift for the duration of turning movement of the driving element 40 following retreat of its pin 41 from a radial slot of element 42 and until ensuing lock of the element 42 against the circularly rounded portion of element 40.

A reversing switch 26 is provided for reversing the rotation of a synchronous motor 20 to cause the transmission to rotate the shaft 15 back and forth. The reversing switch 26 is normally closed at its upper pair of contacts by means of a retractile spring 27.

A coded rotary switch is provided for supplying current to the synchronous motor 20 in periods of different coded lengths of short intervals of time. This rotary switch is characterized by a drum 28 of insulation material fixedly mounted upon a driven shaft 29 of a second synchronous motor 30. The drum 28 is provided with a section comprising short lengths of metallic members 31 set into the insulation material of the drum 28 to rotate therewith. A pair of adjacent fixedly mounted contacts 32 are provided for engaging the metallic members 31 while the tension of spring 27 prevails.

An electric circuit 33 is provided for operating the synchronous motor 20 and includes in series said motor 20, the reversing switch provided by the drum 28, and the contacts 32 which engage the metallic members 31. Current flowing in the circuit will cause the synchronous motor to be continuously operated in one direction and alternate the wave length on which the sender 10 and the receiver 13 will operate. Synchronization between the two automatic means 19 will cause the device to simultaneously operate on the same wave length.

Referring to Fig. 3, three differential phase supply leads are respectively shown at 45, 46 and 47; and these as shown connect by take-off leads 48, 49 and 50 to the synchronous motor 20 and by take-off leads 51, 52 and 53 to the synchronous motor 30. Also to motor 20 are connected leads 54 and 55, the former connected to one of the upper pair of contacts of switch 26, and the latter connected to one of the lower pair of contacts of said switch. That one of the upper pair of contacts 26 other than the one connected to lead 54 is connected by a lead 56 to a main lead 57; while that one of the lower pair of contacts of switch 26 other than the one connected to lead 55 is connected to one of a pair of contacts 32 for engaging metallic members 31 on the rotary switch 28. The other one of this pair of contacts 32 is connected by a lead

58 to another main lead 59. The synchronous motor 30 is connected to main lead 57 by lead 60, and also to the main lead 59 by a lead 61.

Electro-magnetic means is provided for throwing the reversing switch 26 to overcome the spring 27 and open the upper pair of contacts and close the lower pair of contacts of switch 26. This electro-magnetic means comprises an electro-magnet 34 the coil of which is interposed in a circuit subdivision including leads 62 and 63, the latter lead connected to main lead 57. For governing energization of the electro-magnetic means a section on the drum 28 is provided with short metallic members 35 set into the insulation material of the drum 28 each adapted to be engaged by and bridge a pair of adjacent fixedly mounted contacts 36. That one of the contacts of switch 36 other than the one connected in series with the coil of the electro-magnetic means in lead 63 to main lead 57, is connected by a lead 64 to main lead 59. By this arrangement, the metallic members 35 are capacitated to cause current to be intermittently supplied to the electro-magnet 34 to energize the same and reverse the switch 26 in a manner which now should be clear.

It is to be understood that the synchronous motor of each of the automatic means for turning the knobs 12 and 15 must be in complete synchronization with each other to permit the device to be operatively used. This might be accomplished by operating the two automatic means from a common source of electric power or from different sources of electric power having the same cycle phase.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. In combination with a radio sender having a knob which may be turned back and forth for varying the wave lengths of the transmission and a radio receiver having a knob which may be turned back and forth for varying the wave lengths of reception, automatic means for turning each of said knobs back and forth in short periods synchronized with each other, comprising a synchronous motor, a transmission from said synchronous motor to said knob and including a Geneva drive, a reversing switch for said synchronous motor, a coded rotary switch having a section for supplying current to said synchronous motor in periods of different coded lengths of short intervals of time and also having a section for reversing said switch for periods of different coded lengths of short intervals of time, a synchronous motor for driving said rotary switch, an electric circuit for said first named synchronous motor and including in series said reversing switch and the first named section of said rotary switch, electro-magnetic means for throwing said reversing switch, and an electric circuit including in series said electro-magnetic means and the second named section of said rotary switch, and the synchronous motors of each of said automatic means for turning said knobs being in synchronization with each other.

2. In combination with a radio sender having

a knob which may be turned back and forth for varying the wave lengths of the transmission and a radio receiver having a knob which may be turned back and forth for varying the wave lengths of reception, automatic means for turning each of said knobs back and forth in short periods synchronized with each other, comprising a synchronous motor, a transmission from said synchronous motor to said knob and including a Geneva drive, a reversing switch for said synchronous motor, a coded rotary switch having a section for supplying current to said synchronous motor in periods of different coded lengths of short intervals of time and also having a section for reversing said switch for periods of different coded lengths of short intervals of time, a synchronous motor for driving said rotary switch, an electric circuit for said first named synchronous motor and including in series said reversing switch and the first named section of said rotary switch, electro-magnetic means for throwing said reversing switch, and an electric circuit including in series said electro-magnetic means and the second named section of said rotary switch, and the synchronous motors of each of said automatic means for turning said knobs being in synchronization with each other, said transmission comprising a continuously rotating shaft extending from said first synchronous motor, a shaft adjacent said driven shaft a gear mounted on said second shaft, said knob comprising a gear, a sprocket chain between the said gear, and said Geneva drive being mounted between said driven shaft and said second shaft.

3. In combination with a radio sender having a knob which may be turned back and forth for varying the wave lengths of the transmission and a radio receiver having a knob which may be turned back and forth for varying the wave lengths of reception, automatic means for turning each of said knobs back and forth in short periods synchronized with each other, comprising a synchronous motor, a transmission from said synchronous motor to said knob and including a Geneva drive, a reversing switch for said synchronous motor, a coded rotary switch having a section for supplying current to said synchronous motor in periods of different coded lengths of short intervals of time and also having a section for reversing said switch for periods of different coded lengths of short intervals of time, a synchronous motor for driving said rotary switch, an electric circuit for said first named synchronous motor and including in series said reversing switch and the first named section of said rotary switch, electro-magnetic means for throwing said reversing switch, and an electric circuit including in series said electro-magnetic means and the second named section of said rotary switch, and the synchronous motors of each of said automatic means for turning said knobs being in synchronization with each other, said knobs being connected with the variable condensers of said radio sender and radio receiver for rotating these condensers to change the wave length.

4. In combination with a radio sender having a knob which may be turned back and forth for varying the wave lengths of the transmission and a radio receiver having a knob which may be turned back and forth for varying the wave lengths of reception, automatic means for turn-

ing each of said knobs back and forth in short periods synchronized with each other, comprising a synchronous motor, a transmission from said synchronous motor to said knob and including a Geneva drive, a reversing switch for said synchronous motor, a coded rotary switch having a section for supplying current to said synchronous motor in periods of different coded lengths of short intervals of time and also having a section for reversing said switch for periods of different coded lengths of short intervals of time, a synchronous motor for driving said rotary switch, an electric circuit for said first named synchronous motor and including in series said reversing switch and the first named section of said rotary switch, electro-magnetic means for throwing said reversing switch, and an electric circuit including in series said electro-magnetic means and the second named section of said rotary switch, and the synchronous motors of each of said automatic means for turning said knobs being in synchronization with each other, said rotary switch comprising a drum of insulation material, said sections comprising spaced contact members mounted on the periphery of said drum and engaged by spaced contacts.

5. In combination with a radio sender having a knob which may be turned back and forth for varying the wave lengths of the transmission and a radio receiver having a knob which may be turned back and forth for varying the wave lengths of reception, automatic means for turning each of said knobs back and forth in short periods synchronized with each other, comprising a synchronous motor, a transmission from said synchronous motor to said knob and including a Geneva drive, a reversing switch for said synchronous motor, a coded rotary switch having a section for supplying current to said synchronous motor in periods of different coded lengths of short intervals of time and also having a section for reversing said switch for periods of different coded lengths of short intervals of time, a synchronous motor for driving said rotary switch, an electric circuit for said first named synchronous motor and including in series said reversing switch and the first named section of said rotary switch, electro-magnetic means for throwing said reversing switch, and an electric circuit including in series said electro-magnetic means and the second named section of said rotary switch, and the synchronous motors of each of said automatic means for turning said knobs being in synchronization with each other, said knobs being connected with the variable condensers of said radio sender and radio receiver for rotating these condensers to change the wave length.
